UNITED STATES PATENT OFFICE.

FRANK J. BAUMAN, OF DETROIT, MICHIGAN, ASSIGNOR OF ONE-THIRD TO DELBERT M. WHITE AND ONE-THIRD TO HARRY M. LAU, BOTH OF DETROIT, MICHIGAN.

AIRPLANE.

1,307,720.

Specification of Letters Patent. Patented June 24, 1919.

Application filed January 4, 1918. Serial No. 210,356.

To all whom it may concern:

Be it known that I, FRANK J. BAUMAN, a citizen of the United States, residing at Detroit, in the county of Wayne and State of Michigan, have invented a new and useful 5 Airplane, of which the following is a specification.

This invention relates to aerial navigation, and particularly to certain novel features in the structural formation and arrangement of the parts constituting the frame or body of that class of machines known as aeroplanes or airplanes.

The invention has for its principal object 15 to provide a generally improved structure of this character in which the area of the main planes may be increased to effectively add to the sustaining power and carrying capacity of the machine without necessitating 20 a proportionate increase in the general dimensions beyond such as is adopted for machines in common use, and which will be applicable to the structures of present types 25 of machines for navigation of the air or upon the water without materially altering or interfering with the usual means for the propulsion and control of such machines.

In attaining this object the invention contemplates briefly the formation and employment in connection with one or more of the 30 main planes of a centrally and rearwardly extending surface in the form of an elongated body plane of lesser width than said main plane but lying in the plane therewith 35 and connecting said main plane with the tail group for steering and controlling the machine. The body or elongated portion of the plane is provided with a centrally depending longitudinally extending concavo- 40 convex stiffening rib in the form of a trough to serve as a boat or carrying receptacle, and the unitary structure thus formed may be employed singly in connection with suitable driving and controlling means as in a 45 "monoplane", or two or more of the structures may be disposed in spaced parallel relation and secured by suitable frame work in the form of a bi-plane.

The invention also includes such a formation 50 of the main planes as will provide forwardly projecting angular extensions intermediate the center and extremities upon opposite sides thereof to increase the sustaining area of the plane and provide advanced 55 surfaces at such points as will tend to stab-

ilize the machine against axial movement in flight.

Further objects and advantages will appear from the following description in connection with the accompanying drawings, in 60 which one embodiment of the essential features of the invention is illustrated, and in which,

Figure 1 is a plan view of my invention as applied to airplanes of the bi-plane type. 65

Fig. 2 is a front elevation of the structure shown in Fig. 1.

Fig. 3 is a side elevation of the machine showing a portion of the body of the upper plane in section and indicating by dotted 70 lines the application of the propelling and controlling means.

Fig. 4 is an enlarged transverse section taken on dashed line 4-4 of Fig. 3.

Referring to the parts by the characters 75 of reference on the drawings, 1 represents the upper main plane which is substantially T-shaped in plan and extends transversely and longitudinally of the body of the machine. The transverse extensions 2 which 80 form the wings of the main plane are provided at their forward edges with forwardly projecting extensions 3, the edges 4 of which converge respectively toward points intermediate the transverse center of the main 85 plane 1 and the extremities of the wings 2, thus the body areas of the wings are increased by tongue like projections, the angular edges of which offer comparatively 90 slight resistance to penetration of the air while the added surface afforded assists in sustaining and stabilizing the plane in flight.

The longitudinal or body portion 5 of the plane is of lesser width than the main plane 95 from which it extends centrally and rearwardly in the plane thereof and is gradually decreased in width to a point near its extremity where its marginal edges 6 are cut away upon opposite sides of a centrally 100 terminating tail piece 7. The marginal edges of the body plane 5 diverge arcuately adjacent the main plane to increase the area at the point of juncture therewith, and the cut away portions of the margins adjacent 105 the tail piece 7 provide clearance for the mounting and movement of the usual swinging deflectors or elevators 23, as indicated by dotted lines. (See Fig. 1). The members 23 are adapted for manual control 110

through cables 24 respectively connected thereto and extending forwardly therefrom and through openings in the body plane 5 to a control member 25.

Extending longitudinally of the body plane and transversely of the main plane is a centrally depending substantially U-shaped rib or trough-like channel 8 having its free edges 9 flanged outwardly and secured by bolts 10 or rivets 10 to the under face of the main, body and tail portions throughout the length of the structure, as best shown in Figs. 3 and 4. This trough-like channel is tapered rearwardly and rounded upwardly 15 at its forward end in the manner of the hull of a boat, and while serving primarily as a stiffening rib may also be utilized as a carrying body or vessel by closing the ends thereof. However, when the structure is 20 employed as the upper plane of a bi-plane, as shown in the drawings, the ends of the rib 8 are preferably left open to provide an air channel 11 therethrough and render the abridging portion of the body plane 5 effective in adding sustaining surface to the 25 plane.

When this structure is embodied in the lower portion of a bi-plane the body member 12 corresponding to the trough-like rib 30 8 is enlarged and extended forwardly from a point intermediate the ends to a point in advance of the main lower plane 13 and is closed at its forward and rear ends in the form of a boat, the reduced rear portion 14 of which being offset forms a hydroplaning 35 surface for the machine when traveling upon water. The central longitudinal portion of the lower body plane 15, corresponding to the upper body plane 5, is omitted to 40 give access to the body 12, and the marginal sides of this plane which extend laterally from the sides of said body and in substantially parallel spaced relation to the body plane 5 are secured to the marginal 45 edges of the latter by spaced uprights 16 suitably anchored at opposite ends in said members respectively.

The main lower plane 13 which is substantially the same in general form as the 50 upper plane 1, and lies in spaced parallel relation thereto, is centrally divided in line with the body 12 and is secured at its marginal edges respectively to the body plane 15 and to the marginal edges of the upper 55 main plane 1 by spaced uprights 17 which are suitably anchored at opposite ends respectively in said members.

While the structural embodiment of the 60 invention herein illustrated shows the several portions of the planes as formed integral from single members, it will be understood that the plane surfaces may be mounted upon reinforcing ribs or framework as is common, and that such diagonal and 65 transverse stays and braces may be added as

may be required to secure the desired strength and rigidity in the structure.

The motive power and propelling means as indicated by dotted lines at 18 in Fig. 3, and which may be of any suitable form is 70 preferably mounted for operation and control at the forward end of the body or boat of the lower portion of the machine, which may also be provided at the forward end with the usual landing gear 19 and out-rigged floats 20, and at the rear end with tail skid or support 21 and rudder 22, the latter being indicated by dotted lines. 75

The tail 7 of the upper plane may be equipped with elevating and deflecting 80 vanes indicated by dotted lines at 23, which are hingedly mounted to swing angularly relatively and are respectively connected by cables 24 to actuating members 25 arranged for control by the operator as is common. 85

It will appear from the foregoing description of the construction and arrangement of parts that a material increase in the sustaining area of the planes may be effectively attained within the general dimensions of air planes as commonly adopted, and that the employment in connection with the main and body planes of the longitudinally extending trough-like rib, affording an air channel therethrough provides a comparatively light yet strong reinforcement throughout the length of the machine without materially detracting from the sustaining surface of the engaged portions of the plane and without offering undue resistance 100 or interference to the propulsion and control of the machine in the usual manner. 95

What I claim is:

1. An airplane structure comprising a main sustaining plane having a relatively 105 narrow body portion centrally extending rearwardly therefrom, and a trough-like rib extending longitudinally of said body portion and transversely of said main plane and secured to said main and body members to 110 form in conjunction therewith an air channel open at opposite ends thereof.

2. An airplane structure comprising a main sustaining plane having a relatively narrow body portion centrally extending 115 rearwardly therefrom, a channeled rib extending longitudinally of said body portion and transversely of said main portion and open at opposite ends thereof, a second main sustaining plane having a relatively narrow 120 body portion centrally extending rearwardly therefrom, a trough-like rib extending longitudinally of said body portion and transversely of said main planes and closed at opposite ends, and means for securing 125 said planes in spaced superimposed relation.

3. An airplane structure comprising an upper main sustaining plane having a relatively narrow body portion centrally extending rearwardly therefrom, a concavo-convex 130

rib extending longitudinally of said body portion and transversely of said main plane and secured to said main and body planes, a lower main sustaining plane having a relatively narrow body portion centrally extending rearwardly therefrom, and a trough-like rib extending longitudinally of said body portion and transversely of said main plane, said rib being closed at opposite ends and having an opening through the body portion of said main plane, and supporting means for securing said planes in spaced parallel relation.

4. An airplane structure comprising an upper main sustaining plane having a relatively narrow body portion centrally extending rearwardly therefrom, a channeled rib extending longitudinally of said body por-

tion and transversely of said main plane and secured thereto at its free edges, rudders 20 carried by said body portion, a lower main sustaining plane having a relatively narrow body portion centrally extending rearwardly therefrom, a trough-like body extending longitudinally of said body portion and transversely of said main plane, said rib being closed at opposite ends and having an opening through said main plane and its body portion, supporting means for securing said upper and lower main and body planes in 30 spaced parallel relation, and propelling means carried by said body.

In testimony whereof I sign this specification.

FRANK J. BAUMAN.
